UNITED STATES PATENT OFFICE

2,491,615

NEWSPAPER RACK

Robert L. Laird, Corte Madera, Calif.

Application December 16, 1946, Serial No. 716,515

1 Claim. (Cl. 312—57)

1

This invention relates to a newspaper dispensing rack, the primary object of the invention being to provide means controlled by a coin, for selecting a newspaper from a pack of newspapers and delivering the newspaper from the rack, the operation being controlled by the turning of a crank.

An important object of the invention is to provide a device of this character which will protect the newspapers against the elements, the newspapers being removed only by the action of a selecting member operating adjacent to the discharge opening of the housing or container proper.

Still another object of the invention is to provide a newspaper dispensing device wherein the cover may be moved to open the entire top of the container, to permit the newspaper to be positioned within the container with facility.

With the foregoing and other objects in view which will appear as the description proceeds, the invention consists of certain novel details of construction and combinations of parts, hereinafter more fully described and pointed out in the claim, it being understood that changes may be made in the construction and arrangement of parts without departing from the spirit of the invention as claimed.

Referring to the drawings

Figure 1 is a perspective view of a newspaper vending device constructed in accordance with the invention. 30

Figure 2 is a plan view thereof, the cover having been moved to its open position.

Figure 3 is a sectional view taken on line 3—3 of Figure 1. 35

Figure 4 is a fragmental perspective view of the paper selecting roller.

Figure 5 is a fragmental perspective view of the follower that operates within the housing.

Figure 6 is an enlarged sectional detail view illustrating the selector roller as moving the newspaper to a position directly over the discharge opening of the vendor.

Figure 7 is a sectional view taken on line 7—7 of Figure 2. 45

Figure 8 is a fragmental enlarged sectional view taken on line 8—8 of Figure 7.

Figure 9 is a fragmental sectional view through the coin control mechanism, illustrating the mechanism as operated by the action of the coin disposed in the coin chute of the device.

Referring to the drawings in detail, the device comprises a container or housing indicated generally by the reference character 5, the housing 55

having a hinged front wall 6 and a hinged cover 7, the cover 7 and front wall 6 being held closed by means of the hasp 8 which may be locked by means of a padlock not shown.

Secured within the container or housing 5 is a forwardly inclined auxiliary bottom 9 that has its front edge disposed directly above the discharge opening 10 formed along the lower front edge of the main bottom 11, so that newspapers 10 may be delivered from the bottom 9 to the opening. Directly under the opening 10, are the arms 12 which are arranged adjacent to the ends of the container or housing, the arms 12 being inclined downwardly, the free ends thereof being curved upwardly as at 13 providing stops for the newspaper which is delivered through the opening 10 and falls onto the arms 12 which form the rack from which the paper may be removed.

Mounted within the container or housing 5 and arranged adjacent to the end walls 14 thereof are guide rods 15 that have their forward ends secured within the brackets 16, while the rear ends thereof extend downwardly at 17 where they extend through openings in the brackets 18 that are secured to the rear wall 19 of the container or housing 5.

Mounted for sliding movement longitudinally of the guide rods 15, are sleeves 20 that have connection with the side edges of the follower plate 21, through the ears 22 which are secured to the follower plate 21 by means of the screws 23. Thus, it will be seen that due to this construction, the follower plate 21 is held at an oblique angle with respect to the auxiliary bottom 9 to support the newspapers which in the present showing are indicated by the reference character A in inclined positions within the container or housing 5. Extending transversely across the front end of the container or housing 5 is a stop rod 24 that engages the forwardmost newspaper and prevents the upper ends of the newspapers from tilting forward. In other words, the newspapers are held in inclined positions between the rod 24 and follower plate 21, as clearly shown by Figure 3 of the drawings.

The reference character 25 indicates a weighted roller that rests on the auxiliary bottom 9 and engages the follower plate 21 at a point adjacent to the lower edge thereof. The action of this roller is to normally urge the follower plate 21 forwardly to the end that as newspapers are delivered from the container or housing, the follower plate 21 will move forwardly holding the newspapers in a pack.

The reference character 26 indicates the deliv-

ering roll and is shown as having one end mounted in the bearing 27, while the opposite end thereof is mounted in the bearing 28 carried in the partition 29 of the housing.

This delivering roll is disposed along the lower front edge of the auxiliary bottom 9 in spaced relation therewith, and is provided with a line of pins 30 and a plurality of lifter arms 31 arranged at right angles with respect to the pins and with such relation to the pins 30, when the pins contact the lower edge of a newspaper, the pins will separate the foremost newspaper from the pack so that it may be engaged by the lifter arms which follow the pins, the lifter arms operating to carry the newspaper forwardly to a position directly over the discharge opening, where the newspaper is delivered to the arms 12.

Mounted on one end of the roller 26 is a gear 32 which meshes with the gear 33 carried on the inner end of the shaft 34 that extends through one end wall of the container or housing 5, where it is supplied with the handle 35 for operating the shaft 34. Ordinarily the shaft 34 is prevented from movement in one direction, by means of the spring arm 36 which is secured to the bottom of the container or housing 5 and has an inwardly extended finger 37, formed with a lug at its free end, adapted to rest in the recess 38, formed in the shaft 34. The coin chute 39 extends through the top of the container or housing and has its lower end disposed adjacent to the shaft 34 so that a coin positioned in the chute 39 will be delivered to the coin slot 40 formed in the shaft 34. The upper end of the spring arm 36 is bevelled as at 41 to provide a surface against which the coin 42 deposited in the coin slot 40 may engage, moving the arm 36 to a position to cause the finger 37 to be moved from the recess 38, permitting the shaft 34 to rotate and operate the delivering roll 26 to remove a paper.

In order that the shaft 34 will be held against reverse movement, teeth 43 extend therefrom and are engaged by the spring arm 44 that is secured to the bottom of the container or housing.

It might be further stated that the opening or coin slot 40 is of a size so that a coin of the size of a penny, will slide therethrough, while a coin of the size of a nickel will be held in the slot to actuate the mechanism to deliver a paper.

In view of the foregoing, it is believed that in view of the detailed description, the construction and operation of the device will be clear, and that a further description of the device is unnecessary.

What is claimed is:

A newspaper vending machine comprising a container having a delivery opening formed in the bottom thereof adjacent to the front edge of the container, an inclined auxiliary bottom within the container on which the lower edges of a stack of newspapers rest, the front edge of the auxiliary bottom being disposed adjacent to the delivery opening, a delivering roll disposed horizontally of the container and mounted at the lower front edge of the bottom directly over the delivery opening, a line of spaced pins extending from the delivering roll and arranged throughout the length of the roll, lifting arms radiating from the delivering roll extending at right angles with respect to the pins, each lifting arm including a right angled end, said pins separating a newspaper from the stack of newspapers held within the container, delivering the selected newspaper onto the lifting arms, and said lifting arms adapted to force a paper through the delivery opening, as the roll is rotated.
